AUGSBURG NUERMBERG A.-G., OF NUERMBERG, GERMANY.

CYLINDER.

1,110,148.

Specification of Letters Patent. Patented Sept. 8, 1914.

Application filed March 13, 1912. Serial No. 365,069.

To all whom it may concern:

Be it known that I, KARL SCHWARZ, a subject of the German Emperor, residing at Nuremberg, Middle Franconia, Bavaria, Germany, have invented certain new and useful improvements in Cylinders, of which the following is a specification.

This invention has reference to improvements in cylinders for double acting two-cycle internal combustion engines.

One of the great difficulties in the construction of large double acting two-cycle internal combustion engines is the construction of durable cylinders. The strains to which such cylinders are subjected and which cause cracks therein arise from two different sources. First, the changing strains conditioned by the various phases of the combustion in the cylinder which are conducted by the screws into the cast iron parts; and second, the accumulation of heat in certain parts, and unequal expansions to which the cylinders are subjected cause cracks therein. For this reason these cracks occur generally in such locations where both kinds of strains act together, especially in the neighborhood of the valve devices where, in consequence of the unavoidable presence of material and the movements of the valve rods, expansions by the heat and the strain exerted by existing forces occur in very undesirable manner.

The present invention has for its purpose to prevent the terrible strains on the described cylinder parts. This has been primarily attained by an arrangement which releases the parts in question from these strains. For this purpose the screws for securing the cylinder cover are introduced into the cylinder mantle in lines parallel to the axis of the cylinder. The screws are selected so long that they transmit the combustion pressure, acting on the cylinder cover, first upon a flange located below the valves where by the pressure created by the combustion is first transmitted to the middle portion of the cylinder mantle.

In the drawing a cylinder is represented in longitudinal section, which embodies in desirable form the present improvements. The cylinder consists of three parts *a*, *b* and *c*. The two parts *a* and *b* consist each of one half of the inner cylinder wall in connection with that part of the outer cylinder

wall which contains the valve casings *h*. The third part *c* of the cylinder comprises the central portion of the outer cylinder wall which does not contain any valve casings. The covers *d* and *f* are secured to the cylinder by means of the screw bolts *g*, which are so long that they pass longitudinally through the cooling jacket of the cylinder and with their threaded end portions into the central cylinder portion *c*. As a consequence of this arrangement, the pressure acting on the cylinder cover is directly transmitted by means of the screw bolts *g* to the casting *c* and that part of the cylinder mantle which contains the valve casings *h* remains free from this strain. The screw bolts further serve as a connection for the central cylinder portion *c* and the castings *a* and *b*. In addition to the pressure caused by the combustion and acting on the cylinder mantle there is a second strain on said mantle caused by the pressure exerted by the cylinder covers *d*, *f* on the surfaces or shoulders *e* of the inner cylinder wall. As the inner cylinder wall has a slot or opening in the middle for the purpose of creating the exhaust channel or port, said middle portion of the inner cylinder wall can not take up these strains which, therefore, must be transmitted to the outer cylinder wall. However, there is danger that part of this transmission of the strain is taking place through the adjoining valve casings *h* which are already under strain by the heat. In order to prevent this the flanges *k* which connect the outer and the inner cylinder wall at the end of the cylinder are formed so that they represent approximately elements of uniform strength and are adapted to take up the strain resulting from the pressure of the covers and transmit said strain to the outer cylinder wall whereby the valve casings are released. For the purpose of insuring this effect ribs *l* are provided in direct contact with the flanges *k*.

I claim as my invention:

1. A cylinder for double acting two-cycle internal combustion engines composed of two parts, each part consisting of a single piece having an end portion to form a water jacket, and a separate middle portion in the outer wall, two covers for the cylinder ends, and long screw bolts passing each through one cover, the end portion of one cylinder

part and a portion of the water jacket and being secured in the middle portion of the water jacket wall.

2. A cylinder for double acting two-cycle internal combustion engines composed of two parts, each part consisting of a single piece having an end portion to form a water jacket, and a separate middle portion in the outer wall, two covers for the cylinder ends, long screw bolts passing each through one cover, the end portion of one cylinder part and a portion of the water jacket and being secured in the middle portion of the water jacket wall, and flanges connecting the outer and inner cylinder walls.
3. A cylinder for double acting two-cycle internal combustion engines composed of two parts, each part consisting of a single

piece having an end portion to form a water jacket, and a separate middle portion in the outer wall, two covers for the cylinder ends, and long screw bolts passing each through one cover, the end portion of one cylinder part and a portion of the water jacket and being secured in the middle portion of the water jacket wall, flanges connecting the outer and inner cylinder walls, and ribs reinforcing the said flanges to aid in the transmission of strain.

In testimony whereof I affix my signature in presence of two witnesses.

KARL SCHWARZ.
